UNITED STATES PATENT OFFICE.

EDWARD CROW MEEK, OF HUNTINGTON, WEST VIRGINIA.

DESIGN FOR A TRAIN-TIME-INDICATING CABINET.

Application filed March 28, 1925. Serial No. 12,950. Term of patent 3½ years.

To all whom it may concern:

Be it known that I, EDWARD CROW MEEK, a citizen of the United States, residing at Huntington, in the county of Cabell and State of West Virginia, have invented a new, original, and ornamental Design for Train-Time-Indicating Cabinets, of which the following is a specification, reference being made to the accompanying drawing, forming part thereof.

In the drawing:—

The figure is a front elevation of a train time indicating cabinet showing my new design.

I claim:—

The ornamental design for a train time indicating cabinet, as shown.

EDWARD CROW MEEK.
